UNITED STATES PATENT OFFICE.

LEVI C. SMITH, OF WHITESBOROUGH, NEW YORK.

DESIGN FOR A CHEESE-MOLD.

SPECIFICATION forming part of Design No. 29,033, dated July 12, 1898.

Application filed November 4, 1896. Serial No. 611,082. Term of patent 14 years.

To all whom it may concern:

Be it known that I, LEVI C. SMITH, of Whitesborough, in the county of Oneida, in the State of New York, have invented and produced a new and useful Design for a Mold for Manufacturing Cheese, of which the following is a specification, reference being had to the accompanying drawings, showing a part thereof.

Figures 1 and 2 are isometric views looking, respectively, at the top and bottom of a mold, showing my design.

The leading feature of this design consists in a mold for manufacturing cheese, which when viewed in front, rear, and side elevation presents the appearance of a solid rectangle and when viewed in top and bottom plan presents the appearance of a hollow rectangle.

A A' A² A³ represent, respectively, the front, rear, and opposite side walls of a mold embodying this design. The inner and outer faces a a' of said walls are substantially flat and meet, respectively, in substantially sharp

and rounding corners. The lower edges a² of the walls A A' A² A³ are substantially flat, 25 their upper edges a³ are rounding in cross-section and project beyond the outer faces a', and the upper ends of the opposite side walls are formed with ears a⁴, projecting laterally from the outer faces of said side walls. 30

A mold for manufacturing cheese embodying this design presents a novel and characteristic appearance.

What I claim is—

The design for a mold for manufacturing 35 cheese, substantially as herein shown and described.

In testimony whereof I have hereunto signed my name, in the presence of two attesting witnesses, at Syracuse, in the county of 40 Onondaga, in the State of New York, this 23d day of October, 1896.

LEVI C. SMITH.
